LOOM

Filed April 13, 1927

WITNESS

W. H. Bell

INVENTOR,
Arthur J. Harris,

BY
John Stewart,
ATTORNEY

UNITED STATES PATENT OFFICE.

ARTHUR J. HARRIS, OF PATERSON, NEW JERSEY.

LOOM.

Application filed April 13, 1927. Serial No. 183,415.

This invention relates to looms and particularly to that part of their mechanism which is devoted to maintaining taut the advanceable sheet of warp and woven fabric.

5 The principal object is to provide for the letting off of the sheet in an even manner, using mechanism for the purpose that is at once simple and easily manipulated and controlled; the invention, however, is applicable in any case where, given some instrumentality, as the sand-roller, resisting lengthwise movement of such a lengthwise advanceable sheet and a revolute beam, as the cloth-beam, tractively engaged with the sheet and coactive with said instrumentality to tauten the sheet, the beam is subjected to force acting to turn it in the direction to cause such tautening.

In the drawing,

20 Fig. 1 shows in side elevation the warp-beam, cloth-beam, sand-roller and frame of a loom, with the sheet of warp and woven fabric; and

25 Fig. 2 is a side elevation of the invention, partly in section;

Fig. 3 a plan thereof.

In Fig. 1 the warp end portion A of the advanceable sheet is assumed to be tractively engaged by, as by being wound on, the beam 1 and its woven-fabric end portion B to be tractively engaged by, as by being wound on, the beam 2, and 3 is the sand roller forming part of the (take-up) means for advancing the sheet. In the example the instrumentality to resist lengthwise movement of the sheet having coactive therewith either beam to tauten the sheet is assumed to be the sand-roller. This is all according to the usual construction and arrangement. Fig. 1 is present in the drawing simply to afford a graphic representation of the two beams (as 1 and 2) to either of which my invention is applicable. The invention, however, is assumed in the other views to be applied to the beam 1.

45 Given an instrumentality (as 3) having the stated function of resisting lengthwise movement of the lengthwise advanceable sheet A the invention contemplates mechanism to subject the beam on which the sheet of warp and woven fabric is wound to a force active to rotate the beam in the direction to tension the sheet including a revolute worm-wheel having its axis fixed and adapted to be connected with the beam, a revolute worm meshing with the worm-wheel

and being normally urged around the axis of and thereby active on said worm-wheel in the direction to wind the sheet on the beam, and means confining said worm and worm-wheel in their intermeshing relation to each other, in combination with means to rotate the worm in the direction to elevate the same relatively to the worm-wheel. By this construction the worm (or the worm and said means) is directly active, to maintain the tension, and the use of levers in some form or other, which complicates the mechanism, encumbers the loom and by increasing friction produces irregularity in the tension and the let-off action, is avoided.

In Fig. 2, connected (as fixed) to rotate with the beam 1 is a worm-wheel 14 with whose toothed periphery (here affording what I have termed its purchase-affording way) meshes with the thread of a worm 15 which is journaled in a bracket 16 pivoted on a trunnion of the beam; the part 15 normally exerts force (here by gravity) on the gear member 14 and hence on the beam 80 in the direction for causing the latter to tauten the sheet, and to obtain the proper degree of such force any weighting means, as 17, attached to a chain or equivalent 18 extending around and secured to a drum 19 85 on the bracket may be provided.

A ratchet 20 is journaled on the beam trunnion and is adapted to transmit the turning movement to the worm 15 through suitable gearing 21, 22, 23 and 24 of which 21 and 24 are respectively fixed to the ratchet and worm and 22—23 are united to turn together in the bracket 16. A pawl-bar, 25, is suitably supported in any way and is reciprocated from an eccentric 12 on the cam-shaft of the loom. In operation, while the sheet is being advanced, tending of course to rotate the entire system of intergeared parts clockwise in Fig. 2, the pawl-bar turns the ratchet wheel 20 in the opposite direction, resulting in feeding the worm counterclockwise with respect to the worm-wheel and beam. Since the motion of the ratchet wheel is constant, whereas the rate of rotation of said system varies as the operation 100 proceeds due to change in diameter of the wound mass on the beam, a hand-wheel or handle 30 on the worm is provided by which the weaver manually rotates the worm and thus adjusts it around the worm-wheel.

105 It will be apparent that the weaver can readily relieve the tension on the sheet or

restore it by turning the worm, as by its handle 30, in the appropriate direction so that it creeps in the proper direction along the toothed surface of the worm-wheel. (In 5 the dotted-line position of the parts in Fig. 2 the tension has been relieved.)

Having thus fully described my invention, what I claim is:

Mechanism to subject a beam on which is 10 wound one end portion of a sheet consisting for a portion of its length of warp and for the remainder of its length of woven fabric to a force active to rotate the beam in the direction to tension the sheet including a

revoluble worm-wheel adapted to be connected with the beam and having its axis fixed, a revoluble worm meshing with the worm-wheel and being normally urged around the axis of and thereby active on said worm-wheel in the direction to wind the sheet on the beam, and means confining said worm and worm-wheel in their intermeshing relation to each other, in combination with a worm-rotating member concentric and geared with the worm-wheel, and means 20 to rotate said member step by step.

In testimony whereof I affix my signature.

ARTHUR J. HARRIS.
